ELECTRICALLY OPERATED HYDRO- MASSAGING APPARATUS

Rodolfo Jacuzzi, Orinda, Calif., assignor to International
Mfg. Co., Inc., Concord, Calif., a corporation of California

Filed Apr. 28, 1965, Ser. No. 85,000

Term of patent 14 years

(Cl. D83—1)

I claim:

The ornamental design for an electrically operated hydro-massage apparatus, substantially as shown.
